UNITED STATES PATENT OFFICE.

CHARLES EDWARD HAVILAND, OF LIMOGES, FRANCE.

DESIGN FOR A PLATE OR SIMILAR ARTICLE.

SPECIFICATION forming part of Design No. 35,782, dated March 4, 1902.

Application filed February 3, 1902. Serial No. 92,478. Term of patent 7 years.

To all whom it may concern:

Be it known that I, CHARLES EDWARD HAVILAND, a citizen of the United States, residing at Limoges, in the Republic of France, have invented and produced a new and original Design for a Plate or Similar Article, of which the following is a specification, reference being had to the accompanying drawings, forming a part thereof, and in which—

5 Figure 1 is a top elevation of a plate bearing and incorporating my design, and Fig. 2 is a vertical section of same on the dotted line 2 of Fig. 1.

10 The leading feature of my design consists 15 of the ornate shape and configuration of the plate, substantially as shown.

In the drawings, A designates the body of the plate, and B the rim thereof, which rim has the scalloped outer edge and bears at equidistant points the ornate scroll figures C, 20 which follow the outline of said outer edge and are arranged as shown.

What I claim is—

The design for a plate or similar article, substantially as shown and described.

25 Signed at Limoges, in the Republic of France, this 20th day of January, A. D. 1902.

CHARLES EDWARD HAVILAND.
